UNITED STATES PATENT OFFICE

HOMER P. CHANDLER, OF MANSFIELD, OHIO, ASSIGNOR TO THE OHIO BRASS COMPANY,
OF MANSFIELD, OHIO, A CORPORATION OF NEW JERSEY

AUTOMATIC STARTER FOR ELECTRIC MOTORS

Application filed March 2, 1928. Serial No. 258,528.

My invention relates to automatic starters for electric motors.

The main object of my invention is to provide a device having a resistance element which is inserted in the circuit between the electric motor and the source of power to protect the motor from a rush of excess current when current is first delivered to the motor while at rest, and which resistance will be automatically cut out when the motor has reached such speed as the current flowing through the motor and the load on the motor will permit, thereby connecting the motor directly to the source of power.

Another object of my invention is to provide a device which will prevent connecting the motor directly to the source of power for an appreciable time when first starting the motor except through a resistance.

Another object of my invention is to provide a device which has initially inserted between the motor and the source of power a resistance of predetermined value and which it automatically cuts out after the starting current has flowed through the motor for a predetermined length of time.

Other objects of my invention will be disclosed herein and suggest themselves to those skilled in the art as I further describe my invention in detail hereinafter.

My invention resides in the new and novel construction combination and relation of the various elements hereinafter described and shown in the accompanying drawings.

In the drawings:

Fig. 1 is a schematic drawing showing the arrangement of the various circuits as connected to my invention and to an electric motor from a source of power, and also shows schematically the elements of which my invention is composed and their relation to each other.

Fig. 2 is a plan view in detail of the thermally operated and magnetically held switch mechanism which forms a part of my invention and shown as T in Fig. 1.

Fig. 3 is a side view of Fig. 2.

In starting an electric motor from rest it very often happens that there is a load upon the motor considerably in excess of that nec-

essary merely to rotate the armature of the motor and under such circumstances there is always a considerable delay in bringing the motor up to a speed at which the back electromotive force is sufficient to check the initial excess flow of current necessary to start the motor under load, and if this starting current flows for a considerable time, it is very apt to injure or destroy the motor.

For this reason it is common to insert in the circuit between the motor and the source of power some means whereby the initial flow of current through the motor cannot exceed a predetermined amount but which means will be manually or automatically cut out of the circuit when the speed of the motor has passed a predetermined amount or reached a safe value. Such devices are equipped with various means for providing a time element with respect to the cutting out of the device, or in other words, means for compelling the device to remain in protective relation to the motor for a sufficient period of time for safe starting of the motor. My device provides a simple and efficient means of accomplishing the results set forth above and will accomplish other results hereinafter disclosed.

In the preferred embodiment of my invention I provide a self-contained device in which the various mechanisms, parts and elements are mounted upon insulated bases, which in turn are mounted within a frame and which frame is enclosed within a case.

The schematic arrangement of the various mechanisms and elements which I use in my invention and the relation to each other is shown in Fig. 1, mounted within an enclosure and upon a suitable base 1 (see Fig. 2). L' and L'' represent the lines of the main source of power. The motor is shown at M. My device comprises an automatic overload circuit breaker C, a resistor R and a thermally controlled electromagnetically operated and held switch T.

The circuit breaker C is shown of the single pole quick break automatic overload type having terminals 2 and 2' and a switch blade 3 with an operating handle 4. A coil 5 with a movable core 6 will automatically open the

90

95

100

switch C when the current through the coil 5 exceeds a predetermined amount by suddenly raising core 6 which impinges on the trip mechanism of the switch C. The terminal 2 5 is connected to one side of the source of power as, for instance L'' by the conductors 7 and 7' and is controlled, if desired, by the hand operated line switch 8.

The resistor R which has one end connected 10 to the terminal post 9 has the other end normally connected to one end of the coil 5 through a U-shaped bimetal thermostatic element 10 and the conductor 11. The other end of the coil 5 is connected to the switch terminal 2'. Mounted upon the U-shaped element 10 is an adjustable slider 12 by means of which the operation of the thermal element 10 can be controlled as hereinafter explained. Secured to the free end of the element 10 is an armature 13 under control of the electromagnet 14, operated by coil 15 which has one end connected to the terminal 9 by the conductor 16 and the other end connected by the conductor 16' to a fixed terminal 17, fixedly secured to the base or panel and spaced from the element 10. The spaced ends 18 and 19 of the element 10 are fixedly secured to the base and the opposite end is movable with the armature 13 thereon to 25 ward and away from the magnet 14, as the temperature of the element 10 changes. Fixedly secured to the element 10 by a spring element 20' projecting from the lower end of the element 10 (see Fig. 3) and movable therewith but insulated therefrom is a contact 20 adapted to engage with the contact 17 when the free end of the element 10 moves toward the magnet 14. The movable terminal 20 is connected to the terminal 19 by 30 means of the conductor lead 21. When the switch 8 is open and no current is flowing through the device, the lower end of the element 10 with the armature 13 secured thereto is at its remote distance from the magnet 14 and the terminal 20 is out of engagement with the terminal 17 with the elements 17 and 20 closer together than the elements 13 and 14. (See Fig. 3.)

The terminal 9 is connected by means of 50 the conductor 22 to one of the armature poles and the other armature pole is connected to the main line L' by the conductor 23 and the switch 8. One end of the motor field is connected to the conductor 23 by means of the conductor 24 and the other end of the field is connected to the terminal 19 by means of the conductor 25.

From the above description it will be seen 60 that when the switch 8 is open and all other elements are in their normal position that the circuit breaker C will be open and the connection between the fixed contact 17 and the movable contact 20 will also be open, but the resistor will be connected to the blade 65 of the circuit breaker C through the elements

10, 11 and 5 and if the switch 8 is closed and the circuit breaker C is closed, then the current will flow from the source of power through the circuit breaker C, conductor 11, thermal element 10 and slider 12, resistor R 70 and conductor 22 to the motor M and from there through the conductor 23 and switch 8 back to the main circuit. This will form a complete circuit through the various mechanisms and elements of the motor and the motor will start and gain speed, and the thermal element 10 will immediately begin to heat up and its temperature increase through a sustained current flow to the motor as the speed of the motor increases, and the armature 13 75 will gradually approach the magnet 14 and likewise the movable terminal 20 will approach the fixed terminal 17 until finally the sustained current flowing through the elements 10 and 12 will have caused the element 10 to distort sufficiently to contact the terminals 17 and 20. When this takes place the resistor R will be shunted as current will then flow from the terminal 19, through the conductor 21, terminals 20 and 17, conductor 16', coil 15, conductors 16 and 22, to the motor, thus by passing the resistor R and connecting the motor across the main lines L' 80 and L'' by a low resistance path.

Instantly upon the terminals 17 and 20 85 contacting, the coil 15 is energized and the magnet 14 magnetized and will act upon the armature 13, thereby quickly drawing the lower end of the element 10 to its final position, and with it the positive closing of the circuit through the terminals 17 and 20, and so long as current flows through the motor under normal operating conditions, the coil 15 is energized and the circuit through the terminals 17 and 20 positively held closed. If the current for any reason through the parts should suddenly increase beyond a predetermined amount, then the coil 5 will be 90 excessively energized and the plunger 6 will be suddenly raised and impinge upon the latch of the circuit breaker C, thereby releasing the blade 3 and automatically opening the circuit at the contact 2 and de-energizing the coil 15.

The switch 8 may be eliminated if desired and the circuit breaker C depended upon for manually and automatically opening the circuit, depending upon its construction.

I employ the switch T shown in isometric view in Fig. 1 and in detail in Figs. 2 and 3 to control the shunting of the resistor R upon completing the circuit to the motor and to control the closing of said switch T and in order to bring about a delayed action thereof I employ a U-shaped bimetal thermal element 10.

In Figs. 2 and 3 I show a base 1, preferably of insulated material, and upon which is mounted an insulated block 27. Upon the block 27 are mounted two metal standards 1

28 spaced and insulated from each other, and to which are secured the spaced ends 18-19 of the U-shaped thermal element 10 by means of the nuts 29 and 30. To the free end of the bimetal element 10 is the soft iron armature 13 and also to the lower end of the member 10 is the spring conducting member 20', preferably of hard copper or phosphor bronze, and the members 13 and 20' are insulated from the member 10 by means of the insulating members 31 and all are held in relative position by the screws or rivets 32. On the free end of the member 20' is a contact block 20 movable with the member 10. Mounted upon the block 27 is the contact terminal 17 which is engaged by the contact terminal 20.

By means of the adjustable slider 12, the movement of the member 10 is controlled and also the elapsed time at which the resistor R is shunted. By moving the slider 12 away from the fixed terminals 18-19 there is a greater length of thermal element which is affected by the current flow therethrough and consequently the deflection for a given current becomes greater as the slider 12 is moved farther from the fixed terminals.

The electromagnet 14 is provided with a core 33 and end pole members 34. The core 15, one end of which is attached to the contact 17, the other end attached to the terminal 9. The terminal 20 is electrically connected to the terminal 29 of the thermal element by means of the flexible cable 21.

The spacing of elements 17 and 20 is less than that of elements 13 and 34 and therefore 17 and 20 contact while 13 and 34 are still apart. As soon as 17 and 20 engage, full operating current or greater flows between elements 17 and 20, and sparking is liable to occur as element 17 engages element 20 under the very slow movement of the thermal element 10, but immediately upon a contact between elements 17 and 20 the coil 15 is energized and the elements 17 and 20 brought into strong engagement simultaneously with a sliding or wiping movement of the element 20 upon the element 17.

In the relay switch just described current flowing through the thermal element 10 causes the same to heat up, moving the free end thereof toward the pole pieces 34 and the contact 20 toward the contact 17. As soon as the contacts 17 and 20 engage, the resistor R is short circuited and the coil 15 is in series with the motor and, therefore, becomes energized attracting the armature 13 toward the poles 34 and maintaining such relation as long as the coil 15 is energized and the motor operating under normal conditions with the resistor cut out.

The pressure of the contact 20 against the contact 17 due to the spring in the element 20' will tend to prevent sticking of the contacts 17 and 20 when the armature 13 is released.

Fig. 3 shows the thermal relay in its open position with the contacts 17 and 20 separated.

When it is desired to start the motor, the circuit breaker C is closed which is all that is necessary unless the switch 8 is used and it too must be closed and this completes a circuit from the source of power to the motor, and it will be seen from Fig. 1 current will flow from the line L through the conductors 7' and 7 and switch 8, if employed, to the contact 2, thence through the circuit breaker, conductor 11 to terminal 19 of the thermal element 10. Then through the thermal element 10 and out through the terminal 18 to and through the resistor R, then to the terminal 9. The current then passes through conductor 22 to the armature of the motor M and through the conductor 23, switch 8 and conductor 23' to the other power line L'. Field connections for the motor are shown by the conductors 24 and 25.

The resistance of the resistor R is such that it will prevent a rush of current through the motor M but will allow the speed of the motor to become sufficient so that when the resistor R is shunted, the motor will not be subjected to a current flow which is liable to damage it or operate the circuit breaker C. The thermal element 10 is of such capacity and so adjusted that it is not affected by the current flowing therethrough for some appreciable time and which time is sufficient to permit the motor M to assume the maximum speed which the current, controlled by the resistor R, will permit or approximately so. Thermal element 10 is of bimetal which is well known in the art and the current passing through the legs of the thermal element tends to heat the same in accordance with Ohm's law.

It will be evident to those skilled in the art that the adjustment of the thermal element and the spacing of the movable contact from the fixed contact may be such that a given current could flow through the thermal element for an indefinite time without the contacts 17 and 20 engaging as the deflection of the thermal element would not be sufficient, but with other values of current, the contacts would engage after an appreciable time and the lapse of time would depend upon the current value, therefore, the use of the bimetal element permits of a very simple and reliable means of controlling the shunting out of the resistor R with respect to predetermined current and time values.

From the foregoing description it will be seen that I have provided a self-contained motor starter which can be used with a switch 8 if desired, but is not necessary as the automatic switch C, can be used for closing the circuit through the device and to the motor and may also be used for disconnecting the

device from the source of power, and it will also automatically open should the current at any time exceed a predetermined value while the circuit breaker is in the closed position.

- 5 It will also be evident that having closed the circuit breaker C, the current will then flow to the motor M, through the thermal relay switch and the resistor R and this flow will take place until the motor has reached a 10 predetermined speed or approximately the same, and then the thermal relay switch will automatically connect a low resistance by-pass across the resistor r, thereby, in effect, throwing the motor directly across the line. 15 The thermal relay switch will remain in its closed position, thus shunting the resistor R, as long as the motor is running normally and as long as the circuit breaker C remains closed.

I claim:—

- 20 1. A control apparatus comprising a resistor to be connected in a circuit, a by-pass circuit, a fixed contact and a movable contact to connect the said by-pass circuit across the resistor, thermally operated mechanism having a free end to which the movable contact is secured and is insulated therefrom and moved by said mechanism to preliminarily close said contacts and electro-magnetically operated mechanism arranged to be energized 25 when the contacts engage to act upon the thermal mechanism to finally close and hold the contacts closed after the initial closing by the thermal element.

2. A control apparatus comprising a resistor to be connected in a circuit, a circuit to shunt the resistor, a contact mechanism having fixed and movable contacts to connect the shunt circuit around the resistor, thermally operated means in series with the resistor and 35 heated by the current through the resistor to preliminarily close said contact mechanism, the movable contact being secured to the thermal mechanism in insulating relation thereto and movable with said thermal means 40 to engage the fixed contact and electro-magnetic mechanism operated by the current in said shunting circuit acting to finally close and hold the contact mechanism closed and the thermally operated means in its contact 45 closing position.

3. A control device comprising a resistor and means to automatically shunt the resistor after current has flowed therethrough for a predetermined length of time, the said means comprising a U-shaped thermal element, having its closed end free, connected in series with the resistor and adapted to be heated directly by the current flowing in said element, a movable contact secured to the free end of the thermal element in insulated relation thereto and to be moved by said thermal element to engage a fixed contact, and a coil arranged to be energized when the contacts engage and hold the contacts in engagement,

the U-shaped thermal element being shunted when the contacts are in engagement.

4. A control device comprising a deformable thermal element having a limited movement in one direction and a resistor in series, the thermal element being controlled in its movement by current flowing therethrough and through the resistor, contact means controlled by the thermal element to connect a by-pass about the thermal element and the resistor prior to the limit of movement of the thermal element in one direction, and means controlled by the contact means to complete the movement of the thermal element in said direction and maintain the thermal element and resistor by-passed after current has flowed through the thermal element for a predetermined time.

5. In an electric circuit, a resistor, a by-pass circuit therefor, a movable member arranged to complete the by-pass around the resistor, a thermostatic element operated initially by the current flowing through the resistor and arranged to actuate the movable member and close the by-pass and a coil energized by current through the by-pass to operate the thermostatic element to its final position and to hold said movable member in its by-passing position.

6. A control device comprising a resistor, a by-passing circuit and switch normally open when the device is inoperative and having an initial and a final closing position, a thermally controlled element arranged to move the switch to its initially closed position and an electro-responsive mechanism controlled by movement of the thermal element to act upon the thermal element to move the switch to its finally closed position and hold the switch closed and the resistor and thermally controlled element by-passed.

7. An electric control device comprising a resistor to be shunted out, a thermostatic element heated by the current through the resistor, a switch and circuit controlled thereby and actuated by the thermostatic element to shunt the thermostatic element and electro-magnetic means acting upon the thermostatic element and controlled by thermostatic element to maintain switch and thermostatic element in their shunting position.

8. A control device adapted to connect a translating device to a source of electric energy comprising, a resistor, a thermal element having a cold position and a hot position connected in series with the resistor and controlled directly by the current through the resistor, a circuit to by-pass the resistor and the thermal element and a switch operated by the thermal element when hot to connect the by-pass around the resistor and thermal element and electro-magnetic means to hold the switch closed and the thermal element in its hot position.

9. A control device adapted to connect a

translating device to a source of electric energy comprising, a resistor, a thermal element having a cold position and a hot position connected in series with the resistor and controlled directly by the current through the resistor, a circuit to by-pass the resistor and the thermal element and a switch operated by the thermal element when hot to connect the by-pass around the resistor and thermal element and electro-magnetic means to prevent the return of the thermal element to its cold position while the device is functioning.

In testimony whereof I affix my signature.
